C. B. LOGAN.

COMBINED ASSEMBLING AND LASTING MACHINE.

FILED NOV. 17, 1921.

Inventor:
Charles B. Logan.

By
Chas. E. Riordan, Attorney

UNITED STATES PATENT OFFICE.

CHARLES B. LOGAN, OF PALMYRA, PENNSYLVANIA, ASSIGNOR TO THE FOOTWEAR DEVELOPMENT COMPANY, OF PALMYRA, PENNSYLVANIA, A CORPORATION OF PENNSYLVANIA.

COMBINED ASSEMBLING AND LASTING MACHINE.

Original application filed January 18, 1921, Serial No. 438,132. Divided and this application filed November 17, 1921. Serial No. 515,830.

To all whom it may concern:

Be it known that I, CHARLES B. LOGAN, resident of Palmyra, in the county of Lebanon and State of Pennsylvania, a citizen 5 of the United States, have invented certain new and useful Improvements in Combined Assembling and Lasting Machines, of which the following is a specification.

This application is a division of an application filed by me January 18th, 1921, 10 Serial No. 438,132, the present invention relating especially to a mold employed in the combined assembling and lasting a shoe upper having an inturned flange with a shoe 15 sole.

The invention has reference to shoe-making machinery in which an upper is suspended in inverted position within a mold, a last is forced down into the inverted mold, 20 pressure applied so that the upper is shaped to the last, an insole coated with an adhesive supported on the last, an outer sole applied to the insole and the upper, and pressure then applied to the outer sole while the 25 adhesive sets.

The invention is illustrated in the accompanying drawings and will be hereinafter fully set forth.

In the drawings, 30 Figure 1 is a plan view of the mold.

Figure 2 is a section on the line 2—2 of Figure 1.

Figure 3 is a section on the line 3—3 of Figure 1.

The mold comprises a body 50 adapted to 35 rest on the table between the brackets 19 and 22 and having a central opening 51, in which the upper is suspended. The opening 51 corresponds in shape to the shoe and the last 40 is arranged in the opening in the same manner as previously described. Slidably mounted on the top of the mold are wipers 52 which operate substantially at a right angle to the opening 51 and are adapted to 45 fold the edge of the upper over onto the insole, it being understood that an insole is placed on the last, and coated with cement before the last has been forced into position within the upper. To operate the wipers, I

pivotaly mount an angle lever 53 on the 50 mold adjacent each side wiper and one arm of the lever is pivoted to the adjacent wiper while the other arm of the lever extends toward the adjacent side of the mold. The outwardly projecting arms of all the levers 55 are pivoted to a link or push-bar 54 extending to the front of the mold and equipped with a handle 55 of any preferred or convenient form. One of the push bars is provided adjacent its front end with a lateral 60 arm 56 extending toward the central plane of the mold and the free end of this lateral arm is connected by a link 57 with the toe wiper 52. At the opposite side of the mold, the push bar is pivoted at its rear end to a 65 straight lever 58 which is fulcrumed between its ends upon the mold and has its inner end pivotally connected with the heel wiper 52. Gripper fingers 59 are provided upon the 70 mold to stretch the upper and suspend it in the mold.

After the insole has been placed in position, as above stated, the gripper fingers are released and the push bars 54 shoved rearwardly thereby actuating the wipers so that 75 they will move inwardly over the edge of the insole and fold the edge of the upper onto the same. The outersole, coated with cement on its under side, is then placed over the insole and the inturned flange of the 80 upper, after which the presser block is forced down upon the outer sole to hold the parts in contact until the cement sets, after which the shoe is removed and trimmed.

From the foregoing description, taken in 85 connection with the accompanying drawings, it will be seen that I have provided a strong, compact, simple, and easily operated machine by which shoes, particularly those of the "stitchdown" type, may be rapidly 90 lasted and the usual pulling-over machine dispensed with.

It is to be understood that I do not limit myself to the specific details herein described and shown as various minor changes 95 may be made therein within the scope of the appended claims.

Having thus fully described my invention

what I claim as new and desire to secure by Letters Patent of the United States is:—

1. The combination of a mold, gripping fingers mounted thereon, wipers slidably mounted on the mold, and means for moving the wipers toward and from the center of the mold.
- 5 2. The combination of a mold, means for

suspending an upper therein, wipers slidably mounted on the mold and means for moving the wipers toward and from the center of the mold.

10 In testimony whereof I hereunto affix my signature.

CHARLES B. LOGAN.
